CAISSON HEAD

Application filed November 13, 1925. Serial No. 68,817.

This invention relates to hoisting and air-lock apparatus for caissons and particularly to an air-lock head for caissons.

Heretofore, caissons have been provided with air-lock heads and also with means, such as buckets, for hoisting the excavated material, but these have been unsatisfactory when attempted to be operated together due to the cumbersome apparatus and the unreliability of its operation. For example, one method, which requires the services of three or more men, employs an air-lock caisson head having the customary outlet chamber and which is provided with a pulley over which passes the hoisting cable to an engine usually on the ground at a distance from the caisson. Consequently when a loaded bucket is drawn upwardly, the unbalanced sideward pull of the cable causes the caisson head to be subjected to a considerable stress which often causes it to bend and rock as the bucket is raised and lowered. The sideward pull also causes the caisson to deflect somewhat from its intended path as it goes down, unless means are used to counteract this tendency. Moreover such an arrangement occupies considerable space and the scattered apparatus usually interferes with other concurrent operations. The hoisting engine must be properly set with respect to the cable in order that the latter may be run on and off the drum at right angles to its axis.

With such an arrangement the length of the hoisting cable between the engine and the bucket continually changes as the caisson goes into the earth, so that the distance through which the bucket is raised or lowered must be carefully gauged by the operator of the engine to prevent the bucket from striking the top of the caisson head as it comes up or falling upon the operator at the bottom of the caisson as it goes down.

Under these conditions the operator of the engine cannot even have the benefit of any markings on the cable to guide him in winding it up or paying it out unless they be continually altered in accordance with changes in the position of the caisson. In practice, therefore, reliance is placed upon signals between the operators at the caisson

and the engine or upon their skill and judgment in manipulating the apparatus.

The principal object of the invention is to provide a caisson head having all of the necessary operating apparatus in a unitary self-contained structure.

By virtue of this arrangement the entire caisson emplacement apparatus occupies no more superficial area than the caisson proper and requires no external auxiliary apparatus whatever, so that the danger of deflecting the caisson as it sinks is avoided as well as other disadvantages attending the use of such external apparatus. Since the distance between the hoisting apparatus and the bottom of the caisson is constant the hoisting cable may be suitably marked to show when the apparatus should be started or stopped, or automatic means may be employed for giving signals or even for controlling the operation of the apparatus.

The particular nature of the invention as well as other objects and advantages thereof will appear most clearly from a description of the preferred embodiment thereof illustrated in the accompanying drawings, in which like reference characters denote like parts in the several views.

Figure 1 is an external view of an emplaced caisson utilizing the caisson head disclosed by this invention, and

Fig. 2 is a vertical section of the caisson head along the line 2-2 of Fig. 1.

Referring to the drawings, letter A designates the caisson in which excavating is being done under air pressure, and letter B denotes the entire caisson head which is mounted on the caisson A by means of removable bolts 1, whereby the caisson head B is attached to and may be likewise removed from the caisson A.

The air-lock of caisson head B is of the conventional type well known in the art and consists in brief of the built-up steel cylindrical shell 2 which is slightly larger in diameter than caisson A, and having a transverse diaphragm 3 provided with an opening which is closed by the downward swinging lock door 4, hinged at one edge and held in closed position by the counter weight 5 which must be thrown

over to the position shown in Fig. 2 in order to open the lock door 4.

In the wall of cylinder 2 and above the lock door 4 is a discharge door 6 which is opened by sliding it sidewise around the inner wall of the cylinder 2 upon attached wheels 7 which roll upon track 8. A compressed air line 9 passes into the lock chamber of caisson head B and also into the chamber of caisson A. The top 10 of caisson head B is provided with a cable block 11 through which the hoisting cable 12 passes. The caisson head B is provided with joint packing where necessary so as to make it practically hermetically sealed.

In accordance with this invention, a winch is mounted on the top 10 of caisson head B, and which may be either power operated or hand operated as desired, and in the drawings the winch is shown to be power operated for the purposes of illustration. The cable 12 passes through cable block 11 and over pulley 13 which is mounted in a swivel support 14 so as to turn as the cable 12 is wound along winding drum 15, which may be moved along its axle 16 by means of a lead screw for example, so as to wind the cable evenly upon the drum 15, or by any other manner of winding commonly resorted to.

An electric motor 17 may be used for driving the drum 15 and which, for purposes of convenience, may be continuously running and coupled to and uncoupled from the drum 15 by means of lever 18 which operates a clutch disposed in housing 19. Another lever 20 operates reversing gearing, also disposed in housing 19, whereby the rotation of winding drum 15 may be reversed as the bucket 21 is raised and lowered. The entire winch, comprising motor 17, winding drum 15, and clutch and gear housing 19, may be mounted upon one bed plate 22 which is in turn mounted rigidly to the top 10 of caisson head B.

Inasmuch as the type of caisson head illustrated in the drawings is usually of a large size, a scaffold or platform, not shown in the drawings, is erected around the caisson head B, whereby the operating parts thereof become more readily accessible to the operator.

Having described the structure of the caisson head of this invention, the operation thereof will now be explained. Assuming that the excavator in the pit of the caisson A has filled the bucket 21, he gives a hoisting signal, usually by rapping the side of the caisson or by other signalling means, whereupon the winch operator throws the clutch into engagement by means of clutch lever 18, which revolves the winding drum 13 to hoist the bucket 21. When the bucket 21 has passed through the lock at door 4, as is visible to the winch operator through glass ports 23 in the wall 2 of the caisson head, the clutch is disengaged by means of lever 18, lock door 4 is closed by throwing the counterweight 5 to

the position opposite that shown in Fig. 2, door 6 is slid open, and bucket 21 removed for dumping. When discharge door 6 is opened the trapped air rushes out, but the caisson A is closed by lock door 4 and thus a practically constant air pressure is maintained therein.

Having emptied the bucket 21, it is replaced in the caisson head chamber, door 6 is closed whereupon the caisson head chamber fills with compressed air from line 9, gear lever 20 is moved to shift gears to reverse the direction of rotation of winding drum 15, counterweight 5 is thrown over to the position shown in Fig. 2 to open lock door 4, the winch clutch is thrown into engagement by means of lever 18 which lowers the bucket 21 into caisson A, and the winch clutch is disengaged when the bucket 21 reaches the pit of the caisson.

The workman who does the excavating is lowered into the pit of the caisson in the same manner i. e., he steps into the air lock chamber, door 6 is closed after him and the air is turned on gradually and slowly so that his body may adjust itself to the increased external pressure. When the requisite working air pressure is attained he is lowered into the caisson pit through the opening at lock door 4. In emerging from the caisson the above described operation is reversed and the workman is subjected to a gradually and slowly decreasing air pressure down to approximately normal atmospheric pressure before he is allowed to come out of the caisson head. These precautionary measures are necessary because of the disagreeable physical consequences attending the subjection of a person to sudden and considerable increases or decreases in air pressure.

While this specification and the accompanying drawings disclose a specific structure and arrangement of parts, it is to be understood that such disclosure is only employed for the purposes of illustration and that changes may be freely made in the structure and arrangement of parts without departing from the spirit of the invention within the scope of the appended claims. For instance, on account of the constant distance between the winch and the pit of the casing any suitable mechanism for automatically controlling the starting and stopping of the winch may be employed, but as mechanisms for this purpose are well known, none has been illustrated.

I claim:

1. In a hoisting and air-lock apparatus for caissons, the combination with a caisson of an air-lock head joined thereto, a door controlling communication between said caisson and said head, a hoisting means mounted on said head, a cable operable by said hoisting means passing through said head and into said caisson and a carrier suspended from said cable.

2. A hoisting and air lock apparatus for caissons comprising a detachable caisson head, an air lock in said head, externally controlled hoisting means mounted on said head, and a cable and carrier operable by said hoisting means and adapted to pass into said air lock from said caisson and vice versa.

5 3. A caisson head comprising a cylindrical chamber attachable to a caisson shaft, a door 10 disposed transversely of said chamber, a discharge door in the side of said chamber above said first named door, a hoisting winch atop said chamber, a cable adapted to pass through the doorway of said first-named door and 15 operable by said winch, and a carrier attached to said cable.

4. In a hoisting and air-lock apparatus for caissons, the combination of a caisson shaft, a detachable air-lock head attached thereto, 20 a hoisting winch mounted on and exteriorly of said head, and hoisting means operable by said winch passing through said air-lock and into said shaft.

5 5. A caisson head comprising the unitary 25 combination of a caisson air-lock and a winch mounted on the exterior thereof, a flexible element controlled by the winch entering said air-lock and a carrier secured thereto, whereby material may be hoisted from a caisson 30 into the air-lock and vice-versa.

6. A caisson head comprising a cylinder closed at the top and having a trap door at the bottom, a winch mounted atop said cylinder, a cable passing from the winch through 35 the top of the cylinder and through the doorway for said door and operable by said winch, a bucket on said cable, and a door in the side of said cylinder whereby material is discharged after having been hoisted through said first named door and into said cylinder.

40 7. In a head for receiving and discharging materials for caissons, the combination of a shell forming the body thereof, of a trap-door in the bottom of said shell, of a winch 45 mounted on the top of said shell, and of a bucket and cable operable by said winch and passing through said trap-door.

In testimony whereof I affix my signature.
FREDERIC B. GOLDSBOROUGH.
